SILENCER FOR INTERNAL COMBUSTION ENGINES

Wilhelm Petersen Wold, Oslo, Norway, assignor to
 Wilhelm Petersen Wold and Adolf Eger, both of
 Oslo, Norway

Application August 4, 1938, Serial No. 223,130
 In Denmark February 23, 1938

6 Claims. (Cl. 181—55)

The subject of the invention is an improved silencer especially adapted to be fitted to the exhaust pipe of an internal combustion engine. Characteristic to the invention is the feature that the exhaust gases are passed through the silencer without changing their direction to a substantial degree, so that no pressure and power are lost by abrupt change of the direction. In the silencer according to the invention cross walls in the path 5 to be traversed by the exhaust gases are dispensed with and the exhaust gases are not passed along zig-zag lines or forced to change their direction sharply. We have succeeded in reducing the resistance considerably by avoiding abrupt 10 alterations of pressure and eddy motion.

According to the invention in a large elongated chamber, suitably of circular or oval cross-section, is fitted a narrower pipe serving as outlet 15 from the chamber, and shaped to cylindrical or conical form, preferably in the form of a frustum having preferably its reduced open end disposed toward the outlet. The pipe is closed at its opposite end and may terminate freely within the 20 said chamber. In the wall of said pipe are provided several openings having collectively a cross-section equal to the inlet opening. The exhaust 25 gases pass preferably into the large chamber and leave the latter, without altering their general direction of flow, through the openings into the narrow outlet pipe through the open end of which the gases are discharged. In this way the exhaust is divided during its passing through the openings into several currents parallel to each other, substantial loss of pressure being 30 avoided since the total cross-section of the openings is comparatively large and the gases maintain substantially their original direction.

The mouth of the outlet pipe may be widened 35 in the direction of the motion of the exhaust 40 gases so as to secure a gradual passage to the atmosphere.

In a modified construction two pipes may be placed in the elongated chamber, viz., a distributing pipe having a construction known per se 45 by which the exhaust gases are passed from the internal combustion engine into the chamber and an outlet pipe discharging the exhaust gases from the chamber to the atmosphere. Such pipes 50 may, if desired, be made as a unit and be disposed co-axially, the two parts of the pipe being separated from each other by a cross wall.

Silencers of the present construction may expand freely when heated and may be easily assembled for cleaning.

55 With the easier discharge there is obtained

better combustion, and the engine is not inclined to smell even when burning crude oil owing to the fact that the silencer is evacuated at each stroke owing to the small resistance in the silencer.

Further, the cooler is substantially unloaded. An engine, furnished with a silencer in accordance with the invention is silent especially also owing to the fact that there are no surfaces which may reflect sound. Further, an engine furnished with such a silencer uses a smaller quantity of petrol per horse-power unit than the same engine furnished with a silencer of the well known commonly used constructions.

Experiments have proved that 10 to 15% economy is obtained depending upon the size of the engine, that is to say upon the horse-power, the maximum effect being obtained usually by larger engines. The traction force is better and the working is more economical when using a silencer according to the invention than when using commonly employed silencers.

Some forms of the invention are shown by way of example in the accompanying drawing in which:

Fig. 1 shows a silencer for a large engine, for example, an automobile engine.

Fig. 2 shows a silencer for a smaller engine, as for example an engine of a motor cycle.

Fig. 3 illustrates a slightly modified form of the silencer in which a portion of the structure of Fig. 2 is combined with the structure of Fig. 1.

Fig. 4 illustrates a further modification of the structure of Fig. 2.

Fig. 5 illustrates in side elevation a portion of the interior unit of the structure of Fig. 4.

Fig. 6 is a sectional view on the line 6—6 of Fig. 5.

In Fig. 1, 1 designates a cylindrical chamber of a silencer to a rigid end wall of which is connected a branch pipe 2 connectible to the exhaust pipe from an internal combustion engine. A cylindrical or conical outlet pipe is fitted in a removable end wall at the opposite end of the chamber and may be supported by stiffening means. Such outlet pipe 3 extends with a part 4 into the chamber. It may suitably extend to about the central part of the chamber.

The pipes 3, 4 and the pipe 2 may be disposed co-axially relatively to the chamber 1. The end 50 of the part 4 next to the pipe 2 may be closed, preferably by a conical piece 5, in order that the resistance to the inflowing exhaust gases may be as small as possible.

In the wall of the part 4 are apertures 7 for 55

passage of the exhaust gases. The apertures may be arranged in rows and may have a total cross section about as great as the inlet, or better, slightly greater, according to the size of the engine. The gases pass along the paths denoted by arrows 8. It appears immediately from the figure that the exhaust gases flow substantially along stream-lined paths when passing through the silencer.

10 In Fig. 2 is shown a silencer consisting of a chamber having a divided pipe, the first part of which serves as a distributing pipe, while the rear part serves as a discharge pipe from the chamber. In a chamber 9 is fitted a removable 15 conical pipe 10 which is divided into two by means of a wall 11 substantially at the middle part of the pipe. The wall 11 may be plane or may be conical as indicated by dotted lines at 12. With suitable dimensions of the conical part 20 12 the speed of the exhaust gases may remain substantially unchanged during their passage through the first part of the pipe 10.

In the wall of the pipe are openings 13 and 14. That end of the pipe 10 which is connected 25 to the discharge pipe is supported by the end wall 15 of the chamber 9 while its opposite end is supported by its opposite end wall 16. At the discharge end of the pipe there may be arranged a divergent mouth in the form of a funnel 17. The exhaust gases pass along paths indicated by arrows 18.

The shape of the openings may be varied in several ways. They may be bored cylindrically and their axes be arranged at right angles to 35 the axis of the pipe 5 or the pipes 13, 14. However, it is preferred to arrange them in an inclined position.

Further, the openings may be arranged as longitudinal slots, or as cross-slots having inclined edges. They may also be arranged along helical lines. Their walls may be arranged at an acute angle.

The form of the invention shown in Fig. 1 may have combined therewith, if desired, a rearwardly diverging funnel-shaped mouth such as is 45 shown in connection with the structure of Fig. 2 and indicated by the numeral 17. Such modified form of the structure of Fig. 1 is illustrated in Fig. 3 in which the cylindrical chamber is indicated by the numeral 1' having therein the rearwardly tapering pipe 5' provided with apertures 7' and having a portion of its rear end, indicated at 3' extending outside the chamber 1'. This rear portion 3' has connected there- 55 with the rearwardly divergent mouth 20.

The openings of the silencer devices may also have associated therewith deflector hoods such, for example, as is illustrated in Fig. 4, where there is shown a form of silencer corresponding 60 to the one shown in Fig. 2, the cylindrical chamber or body portion of which is indicated by the numeral 9'. Extending through this chamber is the continuously tapering pipe 10' having intermediate its ends a partition 11' and at the two 65 sides of the partition gas outlet and inlet openings 13' and 14', respectively. The rear end of this pipe joins a rearwardly divergent mouth body of conical form which is indicated by the numeral 17'. Surrounding the pipe 10' are two series of deflector hoods, those of the series which is indicated by the numeral 21 encircling the gas outlet apertures 13' and being directed toward the rear of the chamber while those of the other series which is indicated by the numeral 22, encircle 70 the gas inlet apertures 14' and are directed for-

wardly in the chamber so as to receive the gases flowing rearwardly from the rearwardly directed and divergent hoods 21.

Fig. 5 shows how the hoods 21 and 22 may appear in elevation and as shown in this figure, 5 the hoods may extend directly transversely of the pipe of which they form a part, here indicated by the numeral 10'' and corresponding to the pipe 10' of Fig. 4, or the hoods may be disposed obliquely as indicated at 22' if such disposition is found to be desirable.

Fig. 6 illustrates one method of securing the hoods around the pipe 10'' over the apertures therein, the hoods shown upon this pipe and extending at right angles to the axis thereof 15 being designated by the numerals 21' and the apertures which the hoods cover being designated by the numeral 13''.

According to another form the openings may be arranged as longitudinal slots having guide 20 faces.

Instead of using a single outlet pipe, especially in connection with large engines several outlet pipes may be arranged in the same chamber.

I claim:

1. A silencer for combustion engines, comprising a casing forming a chamber, means for introducing engine exhaust gases through one end of the casing into the chamber, a gas conducting conduit in and extending longitudinally of 30 the casing, and having an inner end terminating within the casing and tapering from such end to the other end and having the reduced end extending through a wall of the casing to the exterior thereof to form a gas discharge port, the 35 inner end of the conduit being closed and directed toward the said inlet means and said conduit having apertures formed in the wall thereof in that portion lying within the chamber.

2. A silencer for combustion engines, comprising a casing forming a chamber, means for introducing engine exhaust gases through one end of the casing into the chamber, a gas conducting conduit in and extending longitudinally of 40 the casing and having an inner end terminating within the casing and tapering from such end to the other end and having the reduced end extending through a wall of the casing to the exterior thereof to form a gas discharge port, the inner end of the conduit being closed and directed 45 toward the said inlet means and said conduit having apertures formed in the wall thereof in that portion lying within the chamber, and a hollow funnel-like body connected at its apex with the said reduced end of said conduit and 50 discharging rearwardly therefrom.

3. A silencer for combustion engines, comprising an elongated casing forming a chamber, a pipe extending through the entire length of the casing and having its ends projecting through 60 opposite walls of the casing, said pipe being of constantly decreasing diameter from one end to the other and having a maximum overall diameter materially less than the inside diameter of the casing, the end of larger diameter constituting 65 a gas inlet for the silencer, the end of the pipe of smaller diameter constituting the gas outlet, partitioning means within the pipe, and said pipe having a plurality of apertures in the wall thereof at opposite sides of said partition 70 and lying entirely within the chamber whereby gases entering the inlet end of the pipe will be diverted into the chamber and returned into the pipe for escape through the outlet end thereof.

4. A silencer for combustion engines, comprising an elongated casing forming a chamber, a pipe extending through the entire length of the casing and having its ends projecting through opposite walls of the casing, said pipe being of constantly decreasing diameter from one end to the other and having a maximum overall diameter materially less than the inside diameter of the casing, the end of larger diameter constituting a gas inlet for the silencer, the end of the pipe of smaller diameter constituting the gas outlet, partitioning means within the pipe, and said pipe having a plurality of apertures in the wall thereof at opposite sides of said partition and lying entirely within the chamber whereby gases entering the inlet end of the pipe will be diverted into the chamber and returned into the pipe for escape through the outlet end thereof, the said casing at the end adjacent the outlet end of the pipe being extended beyond the wall through which the outlet end of the pipe passes, and a funnel body connected at its apex with the said outlet end of the pipe and joined to the extended portion of the casing and discharging away therefrom.
5. A silencer for combustion engines, comprising a casing forming a chamber, means for introducing engine exhaust gases through one end of the casing into the chamber, a gas conducting conduit within and extending longitudinally of the casing, said conduit being tapered from one end to the other and having the reduced end extending through a wall of the casing to the exterior thereof to form the gas discharge port, the inner end of the conduit being closed and directed toward the said gas introducing means and said pipe having apertures formed in the wall thereof in that portion lying within the chamber, and deflecting hoods carried by said conduit and extending over said apertures and directed toward the outlet end of the conduit.
6. A silencer for a combustion engine, comprising a casing forming a chamber, means for introducing engine exhaust gases through an end of the casing into the chamber, means forming a conduit within the casing and opening through the opposite end thereof to provide a gas discharge port, the conduit forming means tapering throughout its length toward the said opposite end of the casing and having gas inlet apertures in the portion of the side wall thereof lying within the casing by which gas may flow from the casing into the conduit along paths extending angularly to the path of flow of the gas entering the casing through the first-mentioned end.
